UNITED STATES PATENT OFFICE.

PAUL WERNER FLEISCHER, OF WEST HOBOKEN, NEW JERSEY, ASSIGNOR TO AMERICAN CAN COMPANY, OF NEW YORK, N. Y., A CORPORATION OF NEW JERSEY.

METHOD OF PACKING FOOD PRODUCTS.

1,231,585.

Specification of Letters Patent.

Patented July 3, 1917.

Application filed August 27, 1913. Serial No. 726,849.

To all whom it may concern:

Be it known that I, PAUL W. FLEISCHER, a citizen of the United States, residing in West Hoboken, in the county of Hudson 5 and State of New Jersey, have invented a new and useful Improvement in Methods of Packing Food Products, of which the following is a specification.

This invention relates to an improved 10 method of packing food products and it consists more particularly in the way in which the filled sheet metal can or container and its sheet metal cover are provisionally united prior to and during the sterilizing 15 or processing and subsequently completely sealed. And said invention consists in the several steps constituting said method, hereinafter more fully and completely set forth, and made the subject matter of claims. In the accompanying drawing which forms a part of this specification, Figure 1 is a sectional view of the empty can and its cover. Fig. 2 is a sectional view of the filled can with its cover applied and 20 shown in the act of being provisionally secured by the downward pressure of a suitable instrumentality. Fig. 3 shows the completion 25 of the act of the step started in Fig. 2. Fig. 4 shows the filled can with its cover provisionally secured thereto as in Fig. 3 as when passed into the sterilizing chamber. Fig. 5 shows the filled can after the same 30 has been sterilized and the seam between the cover and can body completed by double-seaming rolls.

In the use of the modern sanitary can it has been customary to temporarily secure the flanged, curled and packing charged cover to the flanged filled can by snapping 35 the cover upon the can, or by passing the can and cover through the first operation of forming the double seam, or by pinching the cover and can flange together at several points in its circumference, the purpose being always to secure the cover to the can in such manner as to permit the escape of the expanded vapors and gases from the can during the sterilizing heat or processing operation, 40 while at the same time the solid contents of the can are kept from exuding or escaping. The present invention, relating as it does to this particular feature of packing of food products, contemplates the securing of the

cover to the can without snapping, without 55 preliminary roller operation, and without pinching the preliminary seam but by a simple downward pressure upon the cover so exerted as to bend outward and expand in diameter the can flange and thus cause said 60 flange to interlock with the incurled edge of the cover. The special advantage of this method lies in the circumstance that it may be applied with a little modification to the ordinary sanitary can and its cover as now 65 largely made, and further in the circumstance that this manner of assembling together and uniting the filled can and its cover is one that lends itself to rapid operation and to the employment of automatic machinery, and to the further circumstance that when the filled can and its cover are thus united and after passing through the sterilizing process the provisional union 70 between the can and cover is left in such 75 form that the ordinary double-seaming rolls for finally closing and sealing the joint can operate perfectly in the ordinary manner. In the said drawing, A represents an ordinary sanitary can having the flange a. B 80 represents the ordinary sanitary can cover having the flange b and incurled peripheral projecting fold b¹ which, as is well known, is placed upon the outer edge of the can cover to guard the packing material, with 85 which this part of the cover is coated, said packing material consisting usually of some flexible adhesive coating and which may be of many kinds. The preserved food contained in the can is represented at C. D 90 represents a suitable instrument for pressing the cover upon the can.

The operation is as follows: First, the can A is supplied with the contents C to be preserved; second, the cover B is placed 95 loosely upon the can with the flange a of the can resting upon the flange b; third, in this condition the cover is pressed smartly down upon the can flange, causing the latter to bend from its inclined position toward 100 the horizontal and thus to expand outwardly into the condition shown in Fig. 3 and Fig. 4 of the drawing, whereby the can and cover are locked together in such manner that the vapor contents and gases expanding 105 may find their way out through the joint but the solid contents will be retained; fourth, the filled can and its pro-

visionally locked cover are subjected to the sterilizing or processing heat; fifth, finally the filled can fully sterilized and its provisionally locked cover are sealed together by forming the provisional seam into the hermetic final seam illustrated in Fig. 5, by the application of the ordinary double-seaming rolls or operation.

It sometimes happens that the packing 10 material is not sufficiently set to resist the scraping action of the flange *a* upon the under surface of the cover flange *b*. In such case the scraping action can be quite overcome by slightly rounding or curling the 15 upper edge of the outstanding can body flange *a*, as shown at *a'*. The curvature need be so slight in actual practice that in its least form it could hardly be indicated in the drawing.

20 Among other advantages of the invention is that the pressing operation, which stretches and expands the inclined flange radially and interlocks together the can body and cover non-hermetically, smooths out many bends, 25 dents and malformations of the body flange, often produced in handling, shipping and otherwise, and brings the body and cover flanges into very close and accurate conformation before the double seaming; so that 30 a perfect hermetic double seam results in cases where it would not be produced by the usual methods; and this preliminary union of the body and cover is performed by a simple and direct die action without the 35 necessity for any crimping mechanism or action thereof on the cover or can.

I claim:

1. The process of closing cans which consists in forming the body and cover elements 40 thereof with seaming flanges, the flange of one element being inturned and the other element being provided with a flared flange, then applying said cover on the end of the body, then bringing such inclined flange 45 toward the horizontal so as to cause it to interlock with said inturned flange part to hold the cover non-hermetically on the body, and subsequently forming said flanges into a double seam.

50 2. The process of closing cans which consists in forming on the body thereof a seaming flange which is inclined outwardly relative to the side wall of the body and is adapted to be included in a double seam, forming 55 a cover with a flange which extends so as to engage under a portion of the flange of the body when the latter has been brought toward a horizontal position, placing such cover on the body, bringing the flange of 60 the body toward a horizontal position so that it engages over a portion of the flange of the cover to hold the cover non-hermetically to the body, and subsequently forming said flanges into a double seam.

65 3. The process of closing cans which con-

sists in forming on the body thereof a flared seaming flange which extends beyond the end of the body and is adapted to be included in a double seam, forming a cover with a flange which extends inward so as 70 to engage under a portion of the flange of the body when the latter has been brought toward a horizontal position, placing such cover on the body, bringing the flange of the body toward a horizontal position so that 75 it is given greater radial extension and engages over a portion of the flange of the cover to hold the cover non-hermetically to the body, and subsequently forming said flanges into a double seam.

4. The process of closing a can body which consists in providing an upwardly flaring flange on the can body, and a depending curled flange about the cover, placing the curled flange of the cover over the 85 flaring flange of the body, and exerting pressure upon the cover to bring the flange of the body to horizontal position with its edge within the curled flange of the cover in non-hermetic engagement.

5. The process of closing a can body which consists in providing an upwardly flaring flange on the can body, and a depending curled flange about the cover, placing the curled flange of the cover over the 95 flaring flange of the body, exerting pressure upon the cover to bring the flange of the body to horizontal position with its edges within the curled flange of the cover in non-hermetic engagement therewith, and bending 100 down the cover flange and body flange to form a double seam.

6. The method which consists in providing an upwardly flaring flange on the body of a can, a depending curled flange on the 105 cover adapted to fit over the upwardly flaring flange on the body, positioning the cover upon said body, exerting pressure upon the cover to bring the flaring flange of the body to horizontal position and interlocking non-hermetic engagement with the curled flange 110 of the cover, and subsequently forming a double seam as an independent operation.

7. The method of closing cans to insure the formation of an efficient tight double 115 seam, which consists in providing an upwardly flaring flange upon the body and a depending curled flange on the cover, positioning the cover upon the body and pressing upon the cover to remove any inaccuracies from the flaring flange and to bring it to horizontal position with its edge in interlocked non-hermetic relation with the curled flange of the cover, and then rolling the interlocked flanges into a double seam.

8. A method of sealing sheet metal containers, which consists in forming the container with a flange inclined from the horizontal and having an outwardly presented edge, forming the cover with a downward 130

curl having an inwardly presented edge, the edge to edge diameter of the container flange being not greater than the edge to edge diameter of the cover flange, loosely applying the said cover to the said container so that the said flanges are presented toward each other, the cover flange being a little lower than the body flange, then compressing the cover upon the container to bring the top flange to a substantially horizontal position and expand the same outward so that it interlocks positively with and above the flange of the cover but leaves space for the exit from the container of gases and portions of its non-solid contents, and then subjecting the interlocked flanges to a double seaming operation whereby the container is hermetically sealed.

9. A method of sealing sheet metal containers, which consists in forming the container body and cover, one with an outwardly extending flared flange and the other with an inwardly extending flange, then, after filling the container, applying the cover to the body so that the said flanges are presented toward each other, then compressing the cover and body together and causing the outwardly extending flange to be expanded by pressure and to interlock with the other flange without forming an air-tight joint, and then, after processing, hermetically sealing the container.

10. A method of sealing sheet metal containers, which consists in forming the container body and cover one with an outwardly extending flared flange and the other with an inwardly extending flange, applying a packing liner between the cover and body, then, after filling the container, applying the cover to the body so that the said flanges are presented toward each other, then compressing the cover and body together and causing the outwardly extending flange to be expanded by pressure and to interlock with the other flange without forming an air-tight joint, preventing the pressure and expansion of said flange from injuring the said liner, and then, after processing, hermetically sealing the container.

50 11. A method of sealing sheet metal containers, which consists in forming the container body with an outwardly extending flared flange, forming the cover with an inwardly extending flange at the under side of its rim, then, after filling the container, applying the cover to the body so that the said flanges are presented toward each other, then compressing the cover upon the body to cause the body flange to be expanded by pressure and to interlock above the cover flange without forming an air-tight joint,

and then, after processing, hermetically sealing the container.

12. A method of sealing sheet metal containers, which consists in forming the container body with an upwardly and outwardly extending flange, forming the cover with an inwardly extending flange at the under side of its rim, applying a packing liner between the cover and body, then, after filling the container, applying the cover to the body so that the said flanges are presented toward each other, then compressing the cover upon the body to cause the body flange to be expanded by pressure and to interlock above the cover flange without forming an air-tight joint, preventing the pressure and expansion of the body flange from injuring the said liner, and then, after processing, hermetically sealing the container.

13. A method of sealing sheet metal containers, which consists in forming the container body with an upwardly and outwardly extending seaming flange, forming the seaming flange of the cover with an inwardly extending flange at the under side of its rim, then, after filling the container, loosely applying the cover to the body so that the said flanges are presented toward each other, then compressing the cover upon the body to cause the body flange to be expanded by pressure and to interlock above the cover flange without forming an air-tight joint, and then, after processing, double seaming and hermetically sealing the container.

14. A method of sealing sheet metal containers, which consists in forming the container body with an upwardly and outwardly extending seaming flange having a smooth terminal portion, forming the cover with an inwardly extending flange at the under side of its rim, applying a packing liner between the cover and body, then, after filling the container, loosely applying the cover to the body so that the said flanges are presented toward each other with the cover flange a little lower than the body flange, then compressing the cover upon the body to cause the body flange to slide on said packing and to interlock above the cover flange without forming an air-tight joint, and then, after processing, subjecting the interlocked flanges to a hermetic seaming operation.

Signed this 23 day of August, 1913, in the presence of two witnesses.
